UNITED STATES PATENT OFFICE

2,511,324

MULTIPLE FILLING AND SEALING DEVICE

Frank Brodsky, New York, N. Y.

Application October 21, 1946, Serial No. 704,754

4 Claims. (Cl. 226—79)

1

This invention relates to filling and sealing devices for containers, and it is an improvement on the filling and sealing device for containers disclosed in my Letters Patent of the United States, Number 2,167,624, issued August 1, 1939.

One object of my present invention is to provide a filling device for a container which will automatically assure a desired level in the filling, and will automatically prevent an overflow.

Still a further object of my invention is to provide a filling device for a container, which device will produce an air cushion over the liquid filled into the container, and thereby keep the level of the liquid at a predetermined height.

Still a further object of my invention is to provide a novel, efficient, filling device for a row of containers, all of them to be filled simultaneously, and provide means to seal a row of containers filled before, operating simultaneously with the filling of said first row, and also provide means to move rows of containers for such continuous, novel and efficient filling and sealing of them.

Still further objects of this invention will be partly apparent and partly pointed out as the specification of the same proceeds, and, among others, I may mention: to provide a device of said several purposes, which still will be simple in construction and operation, which will have long wearing qualities, and in which the parts will be easily removable and replaceable, for cleaning, repairing, and adjusting.

In the drawings forming a part of this specification, and accompanying the same:

Fig. 1 is a side elevational view of a preferred embodiment of my air cushion multiple filling and sealing device;

Fig. 2 is a plan view thereof on a larger scale, portions of the same having been removed;

Fig. 3 is a longitudinal, partly elevational and partly sectional view on a still larger scale, portions having been broken away, or being indicated in an imaginary manner for economy and clearness of showing, the section generally being taken on the line 3—3 of Fig. 2;

Fig. 4 is a transverse, partly elevational, partly sectional view, portions of the device having been broken away, and the section having been taken generally on the line 4—4 of Fig. 3;

Fig. 5 is a detail sectional view of an air cushion filling valve, on still a larger scale than any of the earlier figures;

Fig. 6 is a detail view of a sealing disk receiving and feeding plate used in my device, and

Fig. 7 shows a modification of the sealing disks used in my device.

Referring now to the drawings more in detail,

2

by characters of reference, the numerals 10 and 11 indicate two side walls for the frame structure of my device, interconnected by appropriate cross bars 18, in the front and the rear, adjacent to the bottoms of the side walls, and a cross plate 14 at about the center of the frame walls and in the rear half thereof.

Various cross members or regions are arranged in the operating mechanism of the device between said two frame walls. In the front such cross region, generally indicated by the letter A, the filling operations for the containers, particularly pitchers, cups or the like for which my device is designed, is executed.

15 In the second cross region, generally indicated by the letter B, the sealing of the containers is done, while in the third region, generally indicated by the letter C, the sealing disks for the next sealing operation are placed. A tubular shaft 15 is rotatably arranged between the two walls near the upper rear ends thereof, and being journaled thereon in any appropriate manner, as indicated at 16, and an operating handle 17 is secured at about the center of the shaft 15.

20 Adjacent to the lower inner sides of each of the side walls 10 and 11 are arranged spaced apart frame members 18 and 19, at a portion in the front part of the device, and cross reinforcing hollow square tubes 20 and 21 may connect them to the respective side walls of the frame. Rails 22 and 23 are secured on said inner frame walls 18 and 19 near the bottoms thereof, and a container carrying tray, generally indicated by the numeral 24, may slide on the rails 22 and 23, as by appropriate sliding channels 25 and 26.

25 30 35 40 45 50 55 Tray 24 may have a bottom plate 27, two side walls 28 and 29, front and rear walls 30 and 31, and it may have a plurality of transverse walls 32 by which it is subdivided into transverse compartments 33. In Fig. 3, however, these compartments are formed by substituting said bottom and said transverse walls by independent angle pieces, as will be obvious.

Into each of such compartments may be placed a predetermined number of containers to be filled, as the pitchers 34, shown or diagrammatically indicated in the drawings, and, as will be understood, my device is adapted to fill such a cross row of containers 34 with one operation, and seal the one to the rear of it, filled in the previous operation, simultaneously with said first mentioned filling of a row. In the drawings, six such containers are shown as arranged in one cross row, but, of course, a larger or smaller number may be used, as well as the tray may be

made for a larger or smaller number of cross rows than the six shown in the drawings.

Across the upper front part of the device, a reservoir 35 is placed, preferably in a removable manner, and may be secured thereon by any appropriate means, as by resting the front portion thereof on the transverse side plate posts 36, and the rear portion thereof resting on the top of a rectangular hollow structure 37 (to be described hereinafter) by a reinforcing plate 38 at the bottom of said container.

A plate member 39 may depend from the reinforcing bottom member 38 at the two sides thereof, and may be engaged in an appropriate groove 40 in the respective side wall, whereby a transverse movement of the reservoir 35 will be prevented, and, finally, two securing bars 41 may be arranged at the sides of the reservoir 35, said bars being pivoted, as at 42, and normally being in a downward and forwardly pushed position, as indicated in full lines in Fig. 3, their forward slots 43 engaging securing pins 44 in the respective side walls 10 and 11.

These bars will prevent an upward movement of the reservoir. If it is desired to remove the reservoir, bars 41 will be pulled rearwardly, as by the pins 45a and as indicated by the arrow 45, then turned upwardly on their pivots 42, as indicated by the arrow 46, their open position being shown in dot and dash lines in Fig. 3, and in a fully vertical position in Fig. 2. In this manner, the reservoir may be easily removed, washed, cleansed, sterilized, the same time aerating tubes 51 may also be removed and cleaned, then all replaced and secured in its position.

Across the rear of the reservoir, filling devices, generally indicated by the numeral 47, depend therefrom, one such filling device being provided for each container 34. In the embodiment shown in the drawings, six containers and six filling devices are placed across and underneath of the rear of the reservoir in the region A.

Each of the said filling devices or valves comprises a filling pipe proper 48 secured into the bottom of the reservoir, as by the screw threads 49, and communicating therewith through a respective hole 50 provided in said bottom. In the center of each filling tube 48, a so called aerating or air releasing tube 51 is arranged, projecting through the hole 50 in the bottom of the reservoir above the highest upper level of the liquid in the reservoir, as shown in Fig. 1. The bottom end 52 of the aerating tube is open, and is secured into a cross disk 53 which is integral with an outer tube 54, slideable on the filling tube 48 and having the filling holes 55 around its bottom circumference.

A U-shaped or channel bar 56 is also arranged underneath and across the rear portion of the reservoir 35, said bar having a disk 57 for each filling device or valve 47, and the upper end of the outer tube 54 is secured in said disk, as indicated at 58, said U-shaped cross bar 56 and its disk 57 being upwardly and downwardly slideable over the filler tube 48.

A flanged bushing 59 is arranged around the lower part of each outer tube 54, said bushing carrying resilient sealing disk 60, which may be made of rubber. A relatively strong helical spring 61 is placed between an upper adjustable washer 62 and the flanged bushing 59, said washer also being secured on the outer tube 54 but somewhat below the disk 57, a good portion or space between them being filled by the bottom 56a of the U-shaped cross bar 56.

The use and operation in my machine of these individual filling devices or valves will be understood by the construction described and by the showing in Figs. 4 and 5.

5 In Fig. 4 these devices are shown in a closed normal position, in which the spring 61 is allowed to press the U-shaped bar 56 upwardly, and the rubber sealing disk 60, through its bushing 59, downwardly. In such a position, the lower end 59a of the bushing will engage a ledge or flange 53a on the head 53 of the outer tube 54, and thereby the lower portion of said bushing will close the exit holes or openings 55.

The whole outer tube 54, however, at the end of 15 the filling operation, will be moved upwardly through the upward movement of the U-shaped channel 56, and a ring portion 53b on the upper part of the bottom disk 53 of the outer tube 54 will be pressed across the lower end of the 20 filling tube proper 48, whereby the exit of the liquid from the tank through said tube 48 will be doubly prevented. Angular members 63 may be secured on the reinforced bottom 38 of the reservoir 35, and serve as limits for the upward 25 movement of the channel cross bar 56 (Figs. 3 and 5).

Now, when it is desired to fill a row of containers 34, placed underneath the row of filling devices 47, across the rear of the reservoir 35, 30 channel bar 56 will be pressed downwardly, as indicated by the arrow 64, whereby the outer tube 54 will be moved downwardly, carrying the innermost aerating tube 51 with it, and releasing the exit holes or openings 55 (Fig. 5). At the 35 same time, however, washer 62 will compress spring 61, which will act on bushing 59 and press sealing rubber disk 60 on the top rim 65 of the container 34, thereby sealing the same. In this position, the liquid 66 in the container 35 may 40 freely flow down through the filler tube 48 proper, and out through the exit openings 55 into the container 34.

When, however, the upper level of the liquid in the container 34 reaches a predetermined position, 45 as indicated at 67 in Fig. 5, it will close the filler openings 55, and the compressed air cushion 68, produced thereover, will prevent a further flow of liquid into the container 34. In this manner, it will be seen, each container will 50 be filled to a certain height, and cannot possibly be filled to a smaller or larger extent. The aerating tube 51 will serve to permit the exit of the air from the container 34 at the first part of the filling operation.

55 The downward movement of the U-shaped cross bar 56 will be executed in the following manner: a disk, generally indicated by the numeral 70, is secured near each end of the tubular shaft 15, said disk being loose on the shaft and having the major part of its central position removed, as indicated at 71, thereby practically forming two rings at the two sides of said space 71, with a solid portion 72 of the ring 70 connecting them. An arm or pin 73 is secured across the shaft 15, and may play in the space 71. A second arm 74 is secured into the intact portion 72, carrying roller 75 at its outer end, as well as a slide 76. Said slide is slideable on a long arm 77, pivoted in the front part of the respective 60 side wall, as indicated at 78. It will be seen that, as the center handle 17 of the shaft is turned downwardly, as indicated in an imaginary manner by the arrow 79, arm or pin 73 will engage the intact portion 72 of the ring 70 and will 75 move arm 74 downwardly, as indicated by the ar-

row 80, roller 75 engaging the outer end 77a of the lever 77. At the end of the downward movement of the lever, of the handle 17, and the respective turning of the shaft 15, the respective parts are indicated in an imaginary dot and dash manner at 74a, 75a, 17a, and 77b.

The lever 77, however, carries a hook device 81, adjacent to the respective end of the channel bar 56, and projecting upwardly through an appropriate hole in the bottom 56a thereof. The channel bar 56 also carries a pivoted catch device 82. The inner arm 82a, when turned in an inward direction through an appropriate hole in the side of the channel bar 56, will engage a hole in the top of the hook device 81, as shown in Fig. 2, whereby the hook device 81 will be locked, when desired, to the channel bar 56, and, upon the described movement of the shaft 15 and lever 77, hook device 81 will pull the channel bar 56 downwardly, whereby the same may cause the filling valve to execute the described filling operation.

The same movement of the shaft 15 and its associated parts, as described hereinbefore, will, however, simultaneously execute the sealing of the row of containers previously filled. The previously filled row of containers is illustrated in Fig. 3 at 34a by dot and dash lines, and being in region B.

A cross bar 90 is arranged over the row of previously filled containers 34a, said bar having a rim engaging rounded recess 91 for each container 34a, and a hole 92 for the sealing plunger 93 thereabove, the construction and operation of which will be more fully described presently. Bar 90 is suspended on a parallel bar 94 thereabove.

The upper bar 94 is slideable on two end pins 95, secured in appropriate members 96 of the side wall frame structure. A spring 97 normally pushes the upper bar 94 upwardly. The lower bar 90 is suspended thereon through two pins 98, adjacent to said end pins 95, their lower ends being secured in the lower bar 90, and their upper ends being slideable in the upper bar 94 and carrying a head or nut 99 by which they are suspended, as mentioned.

Closure recesses 91 are arranged in the lower bar 90, one for each container, jar, or pitcher 34a, said recess having a curved portion by which it may fit over the top rim of the jar 34a, as will be understood, to rest thereon and to enclose the same. Said recesses are continued upwardly by the cylindrical openings 92 in the bar 90. A sealing plunger 93 is arranged over each opening 92, having a lower sealing disk head upwardly and downwardly slideable through said hole. Plunger pin or shaft 105 for said head 93 is slideable in the upper bar 94 and is suspended therefrom, as by the nut 106. A spring 107 is interposed between the sealing plunger head 93 and the upper bar 94.

On each of the main operating levers 77 of my device, at the two sides of the same, I arrange a depressing member 108 in alignment with the bar 94 and normally slightly thereabove.

It will be obvious that, when the levers 77 are moved with their outer ends downwardly, as indicated by arrow 80 in Fig. 3, and as has been described hereinbefore, the depressing members 108 will engage the respective ends 94a of the bar 94, and will press the same downwardly against the spring 97, of the end pins 95, on which the bar 94 is upwardly and downwardly slideable, said downward movement of the bar 94 being indicated by the arrow 109. Such a

downward movement of the bar 94 also will press the bar 90, thereunder, downward, by the action of the spring 110, and thereby close the curved lower recesses 91 in the bar 90 on the rims 34b of the containers 34a. It also will be obvious that a further downward movement of the bar 94 will now tightly press the sealing heads 93 into the sealing disk openings 34c of the said containers 34a; this through the action of the springs 107 interposed between the sealing heads 93 and the bar 94.

A comparatively thin sliding feeder plate 111 is arranged over the cross plate 14 in the rear of the machine, having a second thin cover plate 112 arranged thereover, but permitting an easy sliding of the same on the plate 14 and between the same and said cover sheet 112 (Figs. 2, 3 and 6). The front portion of the slideable plate 111 has semi-circular recesses 113, one for each of the containers 34a to be sealed in the row B. A plate moving arm 114 is secured on the same at the two sides thereof, having an upper recess 115 in which may operate the arm 116 secured through the tubular shaft 15, as indicated in Fig. 3. When the handle 17 of said shaft is turned in the direction of arrow 79, as previously described, arm 116 will move forwardly, as indicated by arrow 117, engaging the recess 115 and moving the arm 114 in the same direction, thereby also moving the sealing disk feeding plate 111 in a forward position.

A usual sealing disk 118, well known in this art, and normally made of cardboard or similar material, is placed on the base plate 14 into each recess 113 in the front of the slideable plate 111, and when the same is moved forwardly, it will push the disks 118 over the openings 92 in the bar 90 and said disks may then be pushed through said openings and into the sealing recesses 34c, by the sealing heads 93.

A cross frame or supporting member 119 may be secured above the front bar of the plate 14, and spaced apart therefrom, permitting the slideable plate 111 to move back and forth thereunder. A plurality of apertures are provided in said cross member 119, and over each opening is secured a sealing disk storage cylinder 120, in which are stacked the sealing disks 118, normally resting on the slideable plate 111, but when said plate is moved rearwardly, as indicated by the arrow 121, its front semi-circular recesses 113 will be placed into registering relation with the feeder cylinders 120 and the lowermost sealing disks 118 will enter into the respective recesses 113 and will rest there in the position indicated in Fig. 6. When the feeder plate 111 is moved forwardly, as indicated by the arrow 122, it will push the said lowermost sealing disks over the openings 92 in the bar 94, as has been indicated hereinbefore.

The movements of the described parts, when operating the shaft 15 through a downward or rearward motion 79 of the handle 17, is so timed that first the arm 116 will move the respective sealing disks 118 over the openings 92 and the arm 117 will only then press the bar 94 to such an extent that the sealing heads 93 will enter said openings, whereupon, on a further movement of the arms 117, the sealing heads 93 will tightly press the disks 118 in the respective sealing recesses 34c of the containers.

Upon a return, upward or forward, movement of the handle 17, as indicated by the arrow 123, the arm 116 will move rearwardly, opposite to its earlier movement, and will engage the plate

moving arm 114 in an opposite direction, pushing the same and the plate 111 therewith in the rearward direction of arrow 121.

Upon an adequate rearward movement, new sealing disks 118 will drop into the front recesses 113 of the plate 111 from the stacks in the cylinders 120.

It is to be noted that upon such a reverse, forward movement of the handle 17, as indicated by the arrow 123, the shaft 15 also will be turned in the direction indicated by the arrow 124, opposite to the one described hereinbefore, but this will have no moving effect on the arms 77. Such a movement will not try to move the intermediate arm 74, either, in an opposite direction to the one described hereinbefore (arrow 80), as now would be indicated by the arrow 80a, since disk 70 and arm 74 are loose on shaft 15, and arm 126 will rest on stationary member 125, pulled so by spring 127, while the shaft 15 is permitted to rotate in the direction of arrow 124, swinging pin 116 rearwards, as indicated by arrow 128.

The pin 73, which was active in the rearward turning of the handle 17 (arrow 79), will now, upon a forward turning (arrow 123) be entirely inactive, leaving its engagement with the lever 126, as indicated by the arrow 129. Spring 127 insures a fixed contact between stop 125 and arm 126 during this operation.

The final position of the handle 17, after such forward turning thereof (arrow 123), is indicated in an imaginary manner at 17b.

It will be seen, by observing the described parts and their interaction, that upon the rearward turning of the handle 17 (arrow 79), shaft 15 and its associated parts will act on the lever 77 through the pin 73, and will cause the containers 34 to be filled in the region or cross row A, through the filling devices 47, as has been described hereinbefore.

Before that, however, at the initial rearward turning of the handle 17, the arm 116 will move the feeder plate 111 forwardly, and place the feeding disks 118 under the respective sealing heads 93, and on a further turning of the handle 17 in the direction of the arrow 79, bar 94 will be pressed downwardly and cause the disks 118 to be pressed sealingly into the container recesses 34c, by the action of the sealer heads, as will be understood.

The ends of channel bars 56, operating the sealing mechanism in region A, are resting on the double springs 131 in the vertical housing 132, through the intermediary of the pins 133, slidably in the slots 134 in said housing, and said springs will return the bar 56 into its original position and thereby close the filling devices when the sealing operation is finished and the lever 77 is permitted to return upwardly from its depressed filling and sealing position.

As has been described, the row of containers in the region A are first filled upon the depression of the lever 77 by the rearward turning of the handle 17 (arrow 79), and at the same time, with additional such turning, the earlier filled containers 34a will be sealed in the region B.

Upon a return movement of the handle 17 (arrow 123) the feeder plate 111 will be moved rearwardly (arrow 121), for a refilling of the recesses 113, and with the same movement of the device, the tray 24 will be moved rearwardly with one row of containers, whereby the earlier filled container row will be placed in the region B to be sealed with the next return movement of the handle 17, and the next row of empty

containers, in Figs. 1 and 2 being indicated as the region D, will be placed into the position A, ready to be filled with the said next movement of the handle 17.

5 To effect such a relative movement of the various rows of containers, the upward arm 114, secured on the feeder plate 111, and being the moving member for the same, is extended downwardly, as indicated at 114a, and has a catch 10 lever 135 pivoted at its lower end, as indicated at 136 (Figs. 3 and 4). In the longitudinal ledges 137 of the bottom plate for the tray 24, recesses 138 are arranged, which may be engaged by the teeth 139 at the ends of the pivoted catch 15 levers 135.

The recesses 138 are shaped in such a manner that, upon a rearward moving of the feeder plate 111, and the depending arm 114a therewith, the tooth 139 of the lever 135 will engage 20 the same and will move the tray 24 rearwardly with one row of containers, while upon a reverse forward moving of the feeder plate 111, the tooth 139 will be disengaged from the recess 138 and will have no effect on the tray.

25 On the sides of my device, a stationary pin 140 is arranged for each pivot lever 135, on which it may ride in its rearward operating movement and thereby will be gradually lifted out of engagement with the recess 138. In its 30 final position, arm 135 will rest on said pin, by a recess 141, as indicated in its imaginary rearward dot and dash position 135a.

The spring 150 at the end 77a of lever 77 (Fig. 3) is arranged for steadyng the respective parts, 35 as will be obvious.

In Fig. 7 I show a modified form of my sealing disks, wherein the disks 118 for sealing one row of the mentioned containers, in the case illustrated six of them, are interconnected with web 40 portions 118a, which facilitates their handling. Perforations 118b also may be provided to ease the separation of the disks.

It will be understood that in using this modification, the filling tubes 120 will be provided with 45 appropriate vertical slots to permit the sliding downwardly of the web portions 118a.

It will also be understood that my device may be used not only for jars for cream or molasses, but also for any other kind of appropriate containers, even paper cups, to fill a great plurality of them with speed, regularity and ease.

While I have shown a preferred embodiment of my invention, it is to be understood that changes and variations may be resorted to in the elements, 55 constructions and combinations of my invention, and I reserve my rights to such changes and variations as are within the spirit of this specification, and the scope of the claims hereunto appended.

60 What I claim as new, and want to protect by Letters Patent of the United States, is:

1. In a sealing device for a plurality of containers with open tops and arranged in a row in a spaced apart manner, a chain of sealing disks 65 above the top and at one side of said row of containers arranged in a similar row and spaced apart in a similar manner, a substantially weak interconnection being provided between each two disks in the row, a support for said chain on which 70 it may slide transversely to the row of said containers and into registering relation with their tops, means to push said chain on said support into said registering relation, said means being adapted to so move said chain without disturbing 75 the arrangement of its row, said support having

a recessed portion through which said disks may drop over the tops of the respective containers, means to press said disks on said containers, said pressing means at such operation also breaking said interconnections between the disks.

2. In a device, as set forth in claim 1, portions of said interconnections being removed to further weaken the same at the desired breaking places.

3. In a device, as set forth in claim 1, said means for pushing said chain on its support including a plate slideable on said support and having a leading edge turned toward said chain, an aperture being provided in said edge for each disk adapted to partially encircle the respective disk. 15

4. In a device, as set forth in claim 1, said chain

being formed of an integral piece of relatively easily breakable material, like cardboard, said weakened interconnections between the disks being strips of said material in the axial line of the chain.

5 FRANK BRODSKY.
